AIRPLANE

Application filed September 25, 1929. Serial No. 395,130.

This invention relates to air craft, and has for an object the provision of a novel and efficiently operating type of airplane.

A more detailed object is the provision of an airplane composed of a single wing or airfoil and having a wind tunnel extending therethrough in parallelism with the direction of normal flight, this wind tunnel being adapted to confine the slip stream of the propeller or propellers which are operatively mounted within the tunnel.

A further object is the provision of an airplane having a wind tunnel extending longitudinally therethrough, there being a plurality of propellers operatively mounted within the wind tunnel and coupled to a common drive shaft so that several propellers are adapted to be powered by a single prime mover.

20 A further object is the provision of an airplane having a longitudinally extending wind tunnel as described, intersected by a vertically extending wind tunnel. The propellers are mounted within the intersection of the 25 tunnels and are so arranged that they may be swung so as to bring their axes of rotation optionally into alignment with either of the tunnels, with the result that the propellers may be employed to lower or lift the craft 30 vertically to or from a suitable landing place, or they may be employed to propel the airplane horizontally.

A further object is the provision of an airplane as described, in which the propellers 35 may be swung from one position to the other during flight.

A still further object is the provision of suitable mechanism whereby sufficient mechanical advantage may be gained to develop 40 the relatively heavy forces necessary for turning the propellers from one position to the other.

The invention possesses other objects and 45 advantageous features, some of which, with those enumerated, will be set forth in the following description of the invention's particular embodiment which is illustrated in the drawings accompanying and forming a part of the specification.

50 Referring to the drawings:

Figure 1 is a top plan view of an airplane incorporating the principles of the present invention, portions being broken away to better disclose the internal construction. The propellers are shown in position to drive the 55 airplane horizontally.

Fig. 2 is a top plan view and showing the propellers in the positions assumed thereby when capable of lifting the airplane vertically.

Fig. 3 is a front elevation.

Fig. 4 is a longitudinal, vertical sectional view taken substantially upon the line 4-4 of Fig. 3, with the direction of view as indicated.

In its preferred embodiment, the airplane of the present invention as indicated upon the figures of the drawing, is designed as an amphibian airplane, inasmuch as it is capable of arising from, and alighting upon, either land 70 or water. However, it is to be understood that it is altogether within the scope of the present invention to embody the invention in different types of construction so as to adapt it for use in land planes and hydroplanes. 75

The modification herein disclosed, is in the form of a single enlarged wing 6 approximately two and a half times greater in width than in length, and having rounded ends 7. An aileron 8 is suitably mounted within the after edge 9 of the wing 6 upon each side of the center thereof; and a vertical rudder 11 is disposed adjacent the after edge 9 midway between the ends 7.

Whereas the upper surface 12 of the wing 6 is substantially straight in respect to the transverse dimensions of the airplane, the under surface 13 diverges downward therefrom from the ends 7, with the result that the wing 6 is materially thinner adjacent the ends 7 90 than at points spaced from the ends. Furthermore, an enlarged portion 14 extends downward from the under surface 13, midway between the ends 7. In the amphibian type of plane, this enlarged portion 14 serves as the pontoon whereby the airplane is enabled to rest upon the surface of a body of water. Preferably however, a suitable folding landing-gear 16 is disposed within recesses within the under side of the enlarged 100

portion 14, this landing-gear 16 being of such a nature that it may be extended when desired to permit the airplane to alight upon land and take off therefrom.

The enlarged portion 14 accommodates a longitudinally extending wind tunnel 21 extending the entire length of the wing 6, and also a pilot house 22 immediately thereabove adjacent the forward edge of the wing 6. Also upon each side of the wind tunnel 21, passenger and/or freight-carrying compartments 23 are provided.

A vertical wind tunnel 26 intersects the horizontal wind tunnel 21 and extends completely through the wing 6 and enlarged portion 14. Preferably a pair of shafts 27 in alignment with each other, are journaled transversely of the tunnels 21 and 26 within their intersection, each shaft 27 having a suitable prime mover 28 operatively coupled thereto, these motors 28 being disposed upon each side of the horizontal tunnel 21 and between fore and aft compartments 23. A rigid framework 29 composed of a side bar 31 mounted for free rotary movement upon each of the shafts 27 and end bars 32 joining the two side bars 31, serves as the support for a bank of a plurality of propellers 33. Each propeller 33 is journaled for rotation about an axis perpendicular to that of the shafts 27, and preferably they are arranged in pairs, i.e., the shaft 34 of each propeller 33, is in axial alignment with the shaft 34 of another propeller 33 journaled in the opposite end bar 32. Rotation is imparted to the propellers 33 from the shafts 27, by means of mitre gears 36 carried by the shafts 27, each mitre gear 36 being enmeshed with preferably the mitre gears 37 carried by both aligned propeller shafts 34 of one pair of propellers. Inasmuch as this method of driving the propellers 33 will result in the propellers of each pair being driven in opposite directions, the propellers upon one side of the frame 29 are of left hand pitch, whereas the opposite propellers are of right hand pitch.

A relatively large worm wheel 41 is made fast to the framework 29, and is engaged by a worm 42 which is carried by a shaft 43 which extends forward into the pilot house where it is provided with a hand wheel 44 or equivalent means for imparting rotation thereto.

Covers 46 and 47 are associated with the top and bottom of the vertical wind tunnel 26 respectively, each cover being slidably mounted so as to permit its being optionally placed in registration with the wind tunnel 26 or withdrawn therefrom. Any suitable means for mounting the covers 47, may be employed, such for example as guideways 48 having flanges 49 adapted to slidably engage the outermost faces of the covers 46 and 47 as the case may be. Each cover is provided with a rack 51 enmeshed by a pinion 52 which is carried by a shaft 53 journaled within a

suitable bearing 54 made fast to the structure of the wing 6. Each shaft carries a mitre gear 56 which is enmeshed by another mitre gear 57 carried by an operating shaft 58 which extends to a point closely adjacent the forward edge of the wing 6, and which is also journaled within suitable bearings 59, and carries a mitre gear 61 enmeshed by another mitre gear 62, which in turn is carried by a shaft 63. The shafts 63 extend into the interior of the wing and are connected by suitable mechanism (not shown) to operating mechanism accessible within the pilot house 22, whereby rotational movement may be imparted to the shafts 63, 58, and 53, to permit the operators of the airplane to shift the covers 46 and 47 to desired position.

The operation of the airplane of the present invention is substantially as follows:

When it is desired to take off in flight, the covers 46 and 47 are first withdrawn so as to leave the vertical air tunnel 26 open, and the hand wheel 44 operated so as to turn the worm wheel 41 and framework 29 into that position into which the axes of the propellers 33 are in alignment with the vertical wind tunnel 26. The motors 28 should then be started to impart rotation to the propellers 33, as will be readily understood. Obviously, the direction of rotation should be such that the propellers will lift the airplane vertically upwards, the slip stream of the propellers moving downwards through the vertical wind tunnel 26. When sufficient altitude has been attained, the hand wheel 44 should again be operated to turn the frame 29 so as to bring the axes of the propellers 33 into alignment with the wind tunnel 21, i.e., into alignment with the direction of normal flight. This, of course, will cause the slip stream to pass through the horizontal tunnel 21, the indraft entering at the front of the tunnel and being expelled from the after end, and thus cause the airplane to be driven forward. As the framework 29 is turned into horizontal position, the covers 46 and 47 should be moved back, so as to close the tunnel 26 and thus enhance the streamline design of the airplane.

The airplane may alight by soaring in the conventional manner, or by settling vertically downwards, depending upon the conditions obtaining at the particular point where the pilot wishes to make landing. If the area upon which he desires to land is relatively restricted, he should alight by again turning the framework into vertical position, and opening the vertical wind tunnel 26, and then gradually lessening the speed of his motors so as to permit the airplane to settle. It is obvious therefore, that this arrangement will permit a safe landing to be made upon a relatively small space, as well as to take off from such a location.

Control during flight is attained by means

of the vertical rudder 11 and the ailerons 8, in the conventional manner, it being understood that these airfoils may be operated by mechanism (not shown) accessible within the 5 pilot house 22. However, it is entirely within the scope of the invention to facilitate maneuvering of the airplane by increasing the speed of one motor 28, and decreasing that of the other, so as to assist in turning 10 the airplane toward the side of the slowed motor.

By constructing an airplane according to the principles of the present invention, the problem of efficient streamlining is materially 15 facilitated, inasmuch as the motive power including the motors and propellers, as well as the passengers and freight compartments, and pilot house, are almost completely enclosed within the structure of a single wing, 20 necessitating only a relatively slight projection upon the under surface thereof, in proportion to the over-all dimensions of the wing. The scarcity of angular projections and other structure conducive to destroying 25 streamline design, is best indicated upon Fig. 3; and this feature, coupled with the ability of alighting upon and taking off from landing spaces of relatively small area, imparts to the airplane of the present invention, a 30 high degree of efficiency.

It is to be understood that the details of the invention as herein disclosed, are subject to alteration within the spirit or scope of the appended claims.

35 I claim:

1. An airplane comprising a wing, a horizontal wind tunnel extending therethrough parallel to the direction of flight, a vertical wind tunnel extending through said wing 40 and intersecting the horizontal tunnel, a propeller mounted within the intersection of said tunnels, means for driving said propeller, and means for moving said propeller to bring its axis of rotation optionally into 45 alignment with either of said tunnels.

2. An airplane comprising a wing, a horizontal wind tunnel extending therethrough parallel to the direction of flight, a vertical wind tunnel extending through said wing 50 and intersecting the horizontal tunnel, a bank of propellers mounted within the intersection of said tunnels, means for driving said propellers, and means for moving said propellers to bring their axes of rotation optionally into alignment with either of said 55 tunnels.

3. An airplane comprising a wing, a horizontal wind tunnel extending therethrough parallel to the direction of flight, a vertical 60 wind tunnel extending through said wing and intersecting the horizontal tunnel, a bank of propellers mounted within the intersection of said tunnels, means for driving said propellers, and means for moving said 65 propellers simultaneously to bring their axes

of rotation optionally into alignment with either of said tunnels.

4. An airplane comprising a wing, a horizontal wind tunnel extending therethrough parallel to the direction of flight, a vertical wind tunnel extending through said wing and intersecting the horizontal tunnel, means 70 operable to optionally open or close said vertical tunnel, a propeller mounted within the intersection of said tunnels, means for driving said propeller, and means for moving said propeller to bring its axis of rotation optionally into alignment with either of said tunnels.

5. An airplane comprising a wing, a horizontal wind tunnel extending therethrough parallel to the direction of flight, a vertical wind tunnel extending through said wing and intersecting the horizontal tunnel, means 80 operable to optionally open or close said vertical tunnel, a bank of propellers mounted within the intersection of said tunnels, means for driving said propellers, and means for moving said propellers to bring their axes of rotation 85 optionally into alignment with either of said tunnels.

6. An airplane comprising a single wing, a fuselage extending longitudinally thereof and having a longitudinal and a vertical wind tunnel intersecting therein, a shaft extending transversely of said tunnels at their intersection, a frame mounted for rotary movement about the axis of said shaft, a propeller journalled in said frame for rotation about an axis perpendicular to that of 100 the shaft, means coupling said propeller to the shaft to be rotated thereby, and means for swinging said frame to bring the axis of said propeller optionally into alignment with either of said tunnels. 105

7. An airplane comprising a single wing, a fuselage extending longitudinally thereof and having a longitudinal and a vertical wind tunnel intersecting therein, a shaft extending transversely of said tunnels at their intersection, a frame mounted for rotary movement about the axis of said shaft, a bank of propellers journalled in said frame for rotation about axes perpendicular to that of the shaft, means coupling said propellers to 110 the shaft to be rotated thereby, and means for swinging said frame to bring the axes of said propellers optionally into alignment with either of said tunnels. 115

8. An airplane comprising a single wing, a fuselage extending longitudinally thereof and having a longitudinal and a vertical wind tunnel intersecting therein, a shaft extending transversely of said tunnels at their intersection, a frame mounted for rotary movement about the axis of said shaft, a bank of propellers journalled in said frame for rotation about axes perpendicular to that of the shaft, means coupling said propellers to 120 the shaft to be rotated thereby, a worm wheel 125

carried by said frame, a worm engaging said worm wheel, and means for turning said worm to swing said frame and bring the axes of said propellers optionally into alignment with either of said tunnels.

9. An airplane comprising a single wing, a fuselage extending longitudinally thereof and having a longitudinal and a vertical wind tunnel intersecting therein, a shaft ex-

10. tending transversely of said tunnels at their intersection, a frame mounted for rotary movement about the axis of said shaft, a bank of propellers journalled in said frame for rotation about axes perpendicular to that of

15 the shaft, means coupling said propellers to the shaft to be rotated thereby, a worm wheel carried by said frame, a worm engaging said worm wheel, means for turning said worm to swing said frame and bring the axes of

20 said propellers optionally into alignment with either of said tunnels, and means for optionally opening or closing said vertical tunnel.

10. An airplane comprising a single wing, 25 a fuselage extending longitudinally thereof and having a longitudinal and a vertical wind tunnel intersecting therein, a shaft extending transversely of said tunnels at their in-

30 tersection, a frame mounted for rotary movement about the axis of said shaft, a bank of propellers journalled in said frame for rotation about axes perpendicular to that of the shaft, means coupling said propellers to the shaft to be rotated thereby, a worm wheel

35 carried by said frame, a worm engaging said worm wheel, means for turning said worm to swing said frame and bring the axes of said propellers optionally into alignment with either of said tunnels, a slidably mounted

40 cover associated with each end of said vertical tunnel, and means for moving said covers optionally into or out of register with said vertical tunnel.

In testimony whereof I have signed my
45 name to this specification.

SHERMAN T. ALLEN.
